UNITED STATES PATENT OFFICE.

DAVID GAYNOR, OF BROOKLYN, NEW YORK.

WINDOW-RECEPTACLE.

1,285,116.

Specification of Letters Patent. Patented Nov. 19, 1918.

Application filed December 21, 1915. Serial No. 67,976.

To all whom it may concern:

Be it known that I, DAVID GAYNOR, a subject of the Czar of Russia, and resident of the borough of Brooklyn, county of Kings, city and State of New York, have invented certain new and useful Improvements in Window-Receptacles, of which the following is a specification.

My invention relates to window receptacles for containing food stuffs and the like and has for its object to provide a simple and efficient construction in which the receptacle may normally be maintained in a position in which no part of a window or 10 the exit of an adjacent fire escape is obstructed thereby and which permits said receptacle to be easily moved into registry with and close proximity to said window when access to the interior of said receptacle 15 is desired. My improvement will be fully described hereinafter and the features of novelty will be pointed out in the appended claim.

In the accompanying drawings which 20 illustrate examples of my invention Figure 1 is an elevation of one form of my device combined with a window; Fig. 2 is a horizontal section thereof; Fig. 3 is an elevation similar to Fig. 1 of another form of my invention and Fig. 4 is a horizontal section thereof.

As shown in Figs. 1 and 2 the arrangement comprises a bracket 5 which is pivotally mounted at 6 upon a support 7 attached 25 to the exterior of a building of which the window 8 forms a part. The bracket 5 is formed with a horizontal extension 9 of any suitable form on which the receptacle 10 is supported and to which said receptacle is 30 secured in any suitable manner. The said receptacle 10 may be of any predetermined dimensions and constructed of any suitable material and is preferably provided with a hinged door 11 normally maintained in its 35 closed position for instance by means of a lock or latch 12. The bracket 5 is so proportioned and the support 7 is so located that the receptacle 10 may be swung into registry with and close proximity to the window 8, 40 it being understood that the door 11 is located in that wall of the receptacle which faces the window when this form of my improvement occupies the position shown by full lines in Figs. 1 and 2. In this position 45 as will be readily apparent from said figures, the receptacle 10 and any part thereof, in-

terior or exterior, may be readily reached from a point inside of the window 8, so that articles of food or the like may be readily placed in or removed from said receptacle 60 by simply opening the door 11. When access to said receptacle is no longer desired the bracket 5 is simply swung on its pivots 6 through an arc of approximately 180° to the position indicated by dotted lines in Figs. 65 1 and 2. The parts are so dimensioned and the receptacle is so mounted that when in this latter position the receptacle will lie against the wall of the building out of the way and so as to leave all parts of the window 70 unobstructed by any part of the receptacle or its supporting elements. In order that the receptacle may be locked in the position indicated by dotted lines in Figs. 1 and 2 I may provide the bracket 5 with a 75 lug 13 with which one end of a hook 14 is pivotally connected, the other end of said hook 14 being arranged for insertion into a recess or the like 15 suitably located for instance on the sill 16 of the window 8. It 80 will readily be seen that when this hook 14 is positioned in the recess 15 that the bracket 5 with the receptacle 10 thereon is firmly locked in position against any unintentional movement which might be occasioned by the 85 wind or other causes. If desired another recess 15^a may be provided in the sill 16 and suitably located so that when the hook 14 is positioned therein the bracket 5 and receptacle 10 will be locked in registry with 90 the window in the position shown by full lines in Figs. 1 and 2. This latter arrangement prevents a force exerted accidentally for instance by a person losing his or her balance when placing an article in or removing it from the receptacle from swinging the receptacle and bracket outward and precipitating said person through the window. In some cases the hook 14 may be pivotally connected with the sill 16 and the bracket 100 provided with the recesses 15 and 15^a for the accommodation of said hook, the operation and effect in either case being identical.

In the form illustrated in Figs. 3 and 4 the arrangement comprises two spaced and 105 parallel rails 5^a extending across the window 8 and beyond the same at least in one direction as shown in Fig. 3. The said rails 5^a are located exteriorly of the window and have their ends secured respectively to the 110 window casing and to the wall of the building in any suitable manner as by bolts 6^a.

The upper rail 5^a is preferably located at about the level of the meeting rails of the sashes while the lower rail 5^a is located in close proximity to or even below the sill 16 so that the major portion or all of the lower half of the window is left entirely free and unobstructed. In the form now being described the receptacle 10^a, which in general may be the same as the receptacle 10 is carried by members 7^a on which grooved rollers or wheels 7^b are rotatably mounted, which rollers or wheels are arranged to travel along the rails 5^a and to slidably support the receptacle 10^a thereon. If desired a suitable handle 11^b may be provided for manipulating the receptacle. It will be seen that with the arrangement shown in Figs. 3 and 4 the receptacle 10^a may be caused to travel along the rails in one direction to a position in registry with the window 8 in which all parts of said receptacle are readily reached from inside the window and access to the interior of said receptacle may be had without difficulty and danger. When access to said receptacle is no longer desired it may be moved in the opposite direction to a position out of the way and out of registry with said window it being understood that, if desired, any suitable locking means may be included in the construction for maintaining said receptacle in either or both of its positions against accidental displacement.

In both forms, the construction provides a receptacle located exteriorly of the building and which may be used as a refrigerator or for any other purpose and which is firmly held against falling and which may be readily brought to a position in which no part thereof materially obstructs either the window or the exit opening of an adjacent fire escape. The improvement further fully protects the contents of the receptacle, is proof against dislocation and displacement by the elements and does away with the

practice of placing loose receptacles on fire escapes and window sills which prevails in certain sections of many communities. The danger of injury to persons due to the precipitation of such loose receptacles is also absolutely avoided.

My improvement is thus safe and in use would come well within the requirements of local fire departments and health boards as the same does not interfere with ingress and egress through the window and may easily be kept in a sanitary and clean condition.

If desired the receptacles may be provided with slanting roofs so that rain, melting snow and other moisture will readily flow therefrom.

Various changes in the specific forms shown and described may be made within the scope of its claim without departing from the spirit of my invention.

I claim:

The combination with a window, of a receptacle, a vertical member secured to said window, a pair of ears comprising integral portions of said member and projecting outwardly therefrom at opposite ends, a bracket comprising a horizontal member pivotally secured to the lower ear and an upwardly extending member pivotally secured to the upper ear, an extension forming a horizontal continuation of said horizontal bracket member and extending beneath and secured to the bottom of said receptacle whereby the latter is supported from below and movable into and out of registry with said window, a lug forming a relatively inclined continuation of said horizontal bracket member at its pivoted end, a hook pivotally connected with said lug and means on said window for the accommodation of said hook whereby the receptacle is locked in either of its positions.

In testimony whereof I have hereunto set my hand.

DAVID GAYNOR.
